UNITED STATES PATENT OFFICE

MINNIE FRANCES WERNER, OF INDEPENDENCE, MISSOURI

COLANDER

Application filed April 29, 1930. Serial No. 448,272.

This invention relates to certain new and useful improvements in colanders.

A primary object of this invention is to provide a colander including means associated therewith for mashing, squeezing, and forcing through the apertures of the colander the contents of the colander. Heretofore it has been the practice of housewives in using a colander to squeeze and force the contents 10 of the colander through the perforations of the same by hand, and since, in many instances the contents of the colander being heated are still warm, and oftentimes so hot as to possibly result in the burning of the hand 15 of the housewife, it is necessary to wait until the contents cool, resulting in loss of time and otherwise inconveniencing the housewife.

A very important object of this invention 20 is therefore to enable a performance of all these operations in a more sanitary and satisfactory manner and in the accomplishment of the task in less time than heretofore required.

Other objects and advantages of the invention will become apparent during a study of the following description, taken in connection with the accompanying drawings wherein:

Figure 1 is a view partly in section and partly in elevation of my improved colander,

Figure 2 is a perspective view of a support for the same,

Figure 3 is a top plan view thereof,

Figure 4 is a view partly in section and partly in elevation of a pestle forming part of the invention.

With reference more in detail to the drawings it will be seen that my improved colander comprises a conical vessel or receptacle 1, as shown being formed of metal and perforated, although of course it is to be understood that the same may be made of wire mesh or any other suitable material so as to 40 present the necessary apertures through which the contents of the receptacle may pass.

At its upper open end the receptacle 1 is provided with an annular collar 2 corrugated or otherwise formed to provide threads 3.

A cap 4 is in the nature of annulus U-shaped

in cross section to provide an annular guide channel 8. One leg 6 of the cap is extended and at its extended end is corrugated or otherwise formed to provide threads 7 for threaded cooperation with the threads 3 for retaining the cap in position. The cap 6 is further provided with a suitable handle H.

The main receptacle 1 is also provided with a suitable handle H' at the upper end thereof extending laterally from the receptacle to facilitate lifting the receptacle out of its support and for inverting the receptacle in emptying refuse therefrom.

A pestle 9 formed of wood or any other suitable material consists of a conical body 65 at its upper end merging into an elongated cylindrical neck 10 in turn merging into a ball handle 10'. A metallic wear sleeve 11 is rotatably disposed about the neck. Suitable means for scraping the inner face of the wall 70 of the receptacle 1 is provided and carried by the pestle 9. Such means comprises a single length of wire 12 at one end bent laterally and terminating in an eye 13. In this connection, it is to be noted that the tip of 75 pestle 9 is cut off entirely and smoothly as by a saw or any other suitable means. The laterally disposed eye 13 is operatively connected with the pestle being disposed between said end of the pestle and the removable tip 80 19, a small screw rod 14 passing through the tip and the eye into the body of the pestle as clearly suggested in Figure 4.

The eye 13 loosely fits about the screw 14. At the junction of the body and neck of the 85 pestle the wire 12 is looped about the sleeve 11 as at 15 and then bent laterally as at 16 to merge into an angularly disposed lug portion 17 operable within the channel 8 as suggested in Figure 1. From the lug 19 the wire 90 is bent downwardly and offset outwardly then bent inwardly toward the pestle to provide a scraping portion 18 adapted to engage the inner face of the wall of the receptacle 1.

From the foregoing then it will be seen that 95 the cooked material may be placed within the receptacle 1 and the pestle 9 placed in the receptacle with the parts in that relation suggested in Figure 1. Obviously upon rotating the pestle in a suitable manner, the arm 18 100

scraping the wall of the receptacle 11 will force the material downward from the wall of the receptacle and that portion of the wire 12 between the eye 13 and loop 15 will scrape the sides of the pestle, and thus entirely eliminating the old practice of pressing the material with the hand, and further eliminating the annoying experience of the contents working up over the top of the receptacle.

10 The invention further comprehends the provision of a suitable support for the vessel or receptacle 1, the support comprising a plate 20 having an annular opening formed therein and a flange 20' rising from the plate about 15 the opening, the receptacle 1 being passed through the opening.

The support further includes suitable legs 21, which legs 21 are made of suitable wire or any other desired material bent into a 20 substantial U, the legs of the U crossing one another and at their free ends being welded or otherwise secured to the plate 20, the ends of the legs being passed through tubes T, said tubes being arranged in pairs, and disposed 25 in circumferential spaced relation on the underside of the plate, as shown to advantage in Figures 1 and 2.

Preferably, three of such legs 21 suitably arranged are utilized for supporting the plate 30 20. To rotatably support the receptacle 1 within the support there is provided two or more V-shaped members 22 and 23 respectively. The members 22 and 23 respectively are formed from wire and are extended downwardly from opposite portions of the plate to converge toward one another at their 35 apexes. The free ends of the legs of the members 22 and 23 are suitably welded or otherwise secured to the plate 20, the said members 40 22 and 23 at their apexes cooperating to provide a somewhat conical cradle for the receptacle 1.

A somewhat saucer like member s is supported on said members 22 and 23 at their 45 apexes to provide a rest for receiving the apex or lower end of the receptacle 1 for rotatably supporting the receptacle on the support. The members 22 and 23 are especially adapted to be used as cleaning or scraping members since obviously by grasping the handle 8 and thus rotating the receptacle 1 the contents of the receptacle 1 pressed 50 through the perforations of the receptacle and clinging to the outer face of the wall of the receptacle will be scraped from the outer 55 face of the wall in a manner apparent.

The members 22 and 23 also serve as reinforcement in the event a receptacle substituted for the receptacle 1 be used which 60 substituted receptacle may be made from wire mesh more or less flexible in nature.

From the foregoing then it will be seen that I have devised a thoroughly sanitary and convenient colander, and while I have 65 herein shown and described a preferred em-

bodiment of the invention it is to be understood that the same is susceptible to certain changes, as for example suitable means are provided whereby the legs 21 are detachably secured to the plate 20, as may also be the case with regard to the members 22 and 23 so that the entire colander may be readily assembled or dismantled thus permitting the same to be stored when not in use or packed for shipping without requiring a great deal of space.

Having thus described my invention, what I claim as new is:

1. A colander comprising a conical receptacle, an annular cap for the receptacle, said cap provided with an internal annular channel, a member rotatable within said receptacle, said member having an arm projecting laterally therefrom, said arm at its free end merging into an angularly disposed lug movable within said channel, and means carried by said member for scraping the inner face of the wall of said receptacle, and the surface of the pestle respectively.

2. A colander comprising an apertured receptacle, an annular cap for the receptacle, said cap provided with an internal annular channel, a pestle rotatable within said receptacle, an arm projecting laterally from said pestle, said arm merging into an angularly disposed projection operable within said channel, said projection in turn merging into a scraper extension engageable with the wall of the receptacle.

3. A colander comprising an apertured receptacle, an annular cap for the receptacle, said cap provided with an internal annular channel, a pestle rotatable within said receptacle, an arm projecting laterally from said pestle, said arm merging into an angularly disposed projection operable within said channel, said projection in turn merging into a scraper extension engageable with the wall of the receptacle, and means for scraping the outer face of the wall of the receptacle.

4. A colander comprising an apertured receptacle, an annular cap for the receptacle, said cap provided with an internal annular channel, a pestle rotatable within said receptacle, an arm projecting laterally from said pestle, said arm merging into an angularly disposed projection operable within said channel, said projection in turn merging into a scraper extension engageable with the wall of the receptacle, and means for scraping the outer face of the wall of the receptacle, said last mentioned means including supporting means for the receptacle.

5. In a colander, a plate having an annular opening, supporting legs for the plate, a receptacle fitting within said opening for rotation therein, combined scraper and cradle means suspended from said plate for contact with the wall of said receptacle whereby when said receptacle is rotated the outer

face of the wall of the receptacle may be scraped free of material clinging thereto.

6. In a colander, a plate having an annular opening, detachable supporting legs for the plate, a receptacle fitting within said opening for rotation therein, combined scraper and cradle means suspended from said plate for contact with the wall of said receptacle whereby when said receptacle is rotated the outer face of the wall of the receptacle may be scraped free of material clinging thereto, an annular cap threadedly engaged with the top of the receptacle, said cap provided with an internal annular channel, a pestle rotatable within the receptacle, an arm projecting laterally from the pestle, said arm merging into an angularly disposed projection operable within said channel.

7. In a colander, a plate having an annular opening, supporting legs for the plate, a receptacle fitting within said opening for rotation therein, combined scraper and cradle means suspended from said plate for contact with the wall of said receptacle whereby when said receptacle is rotated the outer face of the wall of the receptacle may be scraped free of material clinging thereto, an annular cap threadedly engaged with the top of the receptacle, said cap provided with an internal annular channel, a pestle rotatable within the receptacle, an arm projecting laterally from the pestle, said arm merging into an angularly disposed projection operable within said channel, and a wall engaging member carried by said arm for scraping the walls during rotation of said pestle, means for securing said arm to said pestle for rotation relative to the pestle, said means including means for scraping the surface of the pestle during rotation of the pestle.

8. A receptacle, a support for rotatably supporting said receptacle, said support including means engaging the outer face of the wall of the receptacle for scraping said face during rotation of the receptacle, a pestle rotatable in the receptacle, scraping means for the inner face of the wall of the receptacle and the surface of the pestle respectively mounted on the pestle for rotation relative to the pestle, said scraping means being operable for preventing the contents of the receptacle from working to the top of the receptacle.

9. A colander comprising in combination a receptacle, a pestle rotatable within the receptacle, and a member engageable with the pestle and rotative relative thereto, said member including a part normally engaging the periphery of the pestle for scraping the same, and a second part normally engaging the inner face of the wall of the receptacle for scraping the latter.

10. A colander comprising in combination a receptacle, a pestle capable of rotative movement within the receptacle, and a mem-

ber engageable with the pestle and including a part engageable with the periphery of the pestle for scraping the latter, and a second part engageable with the wall of the receptacle for scraping the same, means for normally maintaining the second part in engagement with said wall, and means for scraping the outer surface of the wall of the receptacle.

11. A colander including in combination a pestle, a member engageable with the pestle and capable of movement relative thereto, said member including a part normally engaging the periphery of the pestle and capable of functioning as a scraper for the pestle, said member including a second part projecting laterally of the pestle and engageable with the wall of the receptacle of the colander for scraping the latter during movement of the pestle relative to the receptacle.

In testimony whereof I affix my signature.
MINNIE FRANCES WERNER.
